UNITED STATES PATENT OFFICE.

E. B. KELLY, OF GOSHEN, INDIANA, ASSIGNOR TO KELLY FOUNDRY & MACHINE CO., A CORPORATION OF INDIANA.

GRATE.

Application filed February 12, 1927. Serial No. 167,689.

This invention relates to improvements in grates and more specially to that type of grate commonly known as a hand stoker where the grate is arranged on a slant and by operation thereof, the fuel is moved progressively over the surface of the same as it is being consumed. In grates of this type, the green fuel is placed at the upper edge, and then by hand manipulation of the grate 15 this fuel is fed or moved progressively downwardly on the grate until it reaches the bottom, new green fuel being added from time to time at the upper edge of the grate as needed.

Among the features of my invention is the provision of a grate of this type in which the swinging or movable grate bars are provided with quadrant shaped sectors, such sectors forming radiating fins in order to 20 radiate the heat more effectively from the grate and thus prevent deterioration thereof. Such sectors also prevent the grate from clogging since they give a cleaving action in the operation thereof; and they also provide 25 a constant air space through the grate, thus preventing undesired variations in the draft.

Other features of my invention are the improved means for locking or retaining the shaking bar frames in the stationary 30 grate frame.

Other features and advantages of my invention will appear more fully as I proceed with my specification.

In that form of device embodying the 35 features of my invention, shown in the accompanying drawings, Fig. 1 is a top plan view with parts removed, Fig. 2 is a view taken as indicated by the line 2—2 of Fig. 1, Fig. 3 is a view in perspective of a portion 40 of one of the side members of the stationary grate frame, and Fig. 4 is a view in perspective of one end of one of the shaking bar frames.

As shown in the drawings, 10 indicates a 45 substantially rectangular stationary grate frame adapted to support a plurality of shaking bar frames indicated by 11, 11 and here shown as 5 in number. It is to be understood, however, that fewer or more of 50 said shaking bar frames may be embodied in a single grate.

Since the construction and operation of each of the shaking bar frames with the shaking bar therein is substantially the same, 55 I will describe in detail but one.

The shaking bar frame 11 is substantially rectangular in shape and is provided with a series of cross bars 11^a, 11^a. The cross bars 11^a are provided with aligned recesses 11^b and the ends of the frame 11 are provided with similar recesses 11^c. The side members of the frame 10 are provided with similar recesses 11^d in line with those in the shaking bar frame when the same is in place in the stationary frame 10.

The recesses 11^b, 11^c, and 11^d are adapted to receive the rocking or shaking bar 12, which is provided with a series of sector shaped fins 12^a lying between the cross members 11^a of the shaking bar frame. Each 70 of the fins 12^a as stated is sector shaped and its outer curved edge is substantially 70° in length. In the rocking or shaking of the bar 12 the fins 12^a move between the cross members 11^a in a sort of cleaving action. That is, in the rocking of the bar, a portion 75 of each of the sectors 12^a, is always between the cross pieces 11^a so that pieces of ash or fuel can not get caught between them. In this way all clogging of the grate during the 80 rocking of the bars is prevented. In other words, there is no scissors action between the fins 12^a and the cross members 11^a that is likely to catch pieces of fuel or ash or clinker.

On each rocking bar, two of the end fins are provided with extensions as indicated by 12^b to act as stops to limit the upward rocking of the bar. There are also connecting rods 13 joined to such extensions on alternate rocking bars and an operating rod 14 is joined to each set. The operating rod 14 is adapted to be reciprocated by means of lever 15, which is rocked by the manually operable handle 16. It will be seen that 90 when the rod 14 is pulled outwardly by means of the lever 15, alternate rocking grate bars will be rocked upwardly in the position shown by the center and top and bottom bars in Fig. 2. When the lever 15 is released the rocking bars tend to fall down by gravity into the positions occupied by the second and fourth bars in Fig. 2. Such downward movement may be limited by means of a stop 95 17 adapted to engage the lever 15 when it is in.

Each of the frames 11 is positioned or locked in the stationary frame 10 in the following manner. The side members of this frame are provided with a series of 110

bosses or lugs 18, each having an upwardly projecting part 18^a to form the two shoulders 19 and 19^a, the latter being undercut as shown. The corners of the frame 11 are provided with suitable recesses 119 and 119^a as shown, to accommodate the parts 18^a on the lugs 18. The end of the frame 11 is put in place to rest on two of the lugs 18 with the shoulders 19^a lying in the recesses 119^a on the frame. The other corners of the frame are then dropped down onto the adjoining lugs 18 until the shoulders 19 are located in the recessed corners 119. In this way each of the frames 11 rests securely in the frame 10, although removal is easily permitted by raising the two lower corners to lift them off of the lugs 18, whereupon the upper corners may be moved out from under the overhanging shoulders 19^a and 20 the frame 11 completely lifted out of the stationary frame 10.

As stated before, alternate rocking bars are preferably connected by a link 13 and each set is preferably adapted to be rocked 25 by means of a rod 14 and operating lever 15. In the operation of the grate, assuming that the rocking bars are all down, green coal is placed on the stationary plate 20 at the upper edge of the grate. The second 30 and fourth bars from the top are then rocked upwardly and allowed to return. This substantially empties these bars from material. The first, third, and fifth bars are then rocked upwardly as shown in Fig. 2 and allowed to return. This transfers material from the first bar onto the second, from the third onto the fourth and so on. This leaves the top bar substantially free from material and the green coal previously placed on the 40 plate 20 and consequently preheated to a certain extent is then pushed down onto the first bar manually. The operation is then repeated. It will be seen, therefore, that in this manner the fuel is gradually moved 45 downwardly on the grate until it reaches the ash plate 21 at the bottom, from which the ashes are dumped in the usual manner.

It is to be particularly noted that the sector shaped fins 12^a extend downwardly 50 some distance below the grate when the

rocking bars are down in the position shown by the second and fourth bars in Fig. 2. This is their normal position, and in this position it will be seen that they act as heat radiating fins, serving to assist in keeping 55 the rocking bars cool.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as 60 broadly as possible in view of the prior art.

What I claim as new, and desire to secure by Letters Patent, is:

1. A grate of the character described comprising; a main supporting frame; a smaller stationary rectangular removable frame mounted in the main supporting frame, said removable frame including parallel side bars with parallel spaced cross bars having aligned recesses in their upper surfaces; and a shaft rotatably supported in the recesses in the cross bars of the removable frame, said shaft being equipped with sector-shaped fins lying between said cross bars. 70

2. A grate of the character described comprising; a main supporting frame provided with side bars having recesses therein; a smaller stationary rectangular removable frame mounted between the side bars of the main frame, said removable frame including parallel side bars with parallel spaced cross bars having aligned recesses in their upper surfaces; and a shaft rotatably supported in the recesses in the cross bars of the removable frame, said shaft being equipped with sector-shaped fins lying between said cross bars, the ends of said shaft extending beyond the ends of the removable frame and lying in the aforementioned recesses in the side bars of the main supporting frame. 80

In witness whereof, I have hereunto set my hand this 9th day of February, A. D. 1927.

R. B. KELLY.
